UNITED STATES PATENT OFFICE

124,834

DESIGN FOR A THERAPEUTIC LAMP

Frank Furedy, Chicago, Ill., assignor to Sun-Kraft, Inc., Chicago, Ill., a corporation of Illinois

Application November 1, 1940, Serial No. 96,247

Term of patent 3½ years

To all whom it may concern:

Be it known that I, Frank Furedy, a citizen of the United States, residing at Chicago, Cook County, Illinois, have invented a new, original, and ornamental Design for a Therapeutic Lamp, of which the following is a specification, reference being had to the accompanying drawing, forming a part thereof and wherein:

The dominant feature of the design resides in the base portion illustrated in solid lines.

I claim:

The ornamental design for a therapeutic lamp, substantially as shown and described.

FRANK FUREDY.
